Patented Sept. 16, 1919.

Inventor,
Frederick J. Hacker, by
G. C. Kennedy,
Attorney.

UNITED STATES PATENT OFFICE.

FREDERICK J. HACKER, OF WATERLOO, IOWA.

GUTTER.

1,316,301.

Specification of Letters Patent. Patented Sept. 16, 1919.

Application filed May 20, 1919. Serial No. 298,397.

To all whom it may concern:

Be it known that I, FREDERICK J. HACKER, a citizen of the United States of America, and a resident of Waterloo, Blackhawk county, Iowa, have invented certain new and useful Improvements in Gutters, of which the following is a specification.

My invention relates to improvements in gutters, and the object of my improvement is to provide a removable covering for the troughed surface of a corrosible metal gutter, adapted to preserve the latter from the corrosion incident to the flow of water thereover.

This object I have accomplished by the means which are hereinafter described and claimed, and which are illustrated in the accompanying drawing, which is a perspective view of a portion of a troughed metal gutter having my improved covering positioned upon and removably secured to its troughed surface.

The gutter 1 is longitudinally troughed, and may be of any desired cross-section and of any material, but as illustrated, depicts the gutter as formed from galvanized iron as commonly employed therefor.

One longitudinal edge of the gutter 1 is bent over inwardly at 2 to provide a spaced flap or open fold, the other longitudinal edge being similarly bent over inwardly and then again bent upwardly to provide a doubled fold 3—4, the outer part of said

edge then being shaped into a cylindrical roll 5, although the latter may be omitted, or otherwise formed.

The numeral 6 denotes a covering sheet, positioned upon the troughed surface of the gutter 1, conformably, and having its opposite longitudinal edges inserted into the open flaps or folds 2 and 3—4 respectively, a little space 7 within said fold 2 being left to allow for differential expansion and contraction of the gutter and said covering 6.

The covering sheet 6 may be made of any waterproof material, such as fiber board impregnated or coated with an impervious substance. This sheet 6, being troughed, receives rain water and conducts it away from a structure, keeping the troughed part of the gutter dry and free from rust or corrosion, as the longitudinal edges of the sheet 6 are covered and sealed by the folds 2 and 3—4.

Having described my invention, what I claim as new, and desire to secure by Letters Patent, is:

The combination with a troughed metal gutter, of a covering therefor positioned upon its inner surface, said gutter having both its longitudinal edge parts folded over inwardly to receive and detachably secure the longitudinal edge parts of said covering.

Signed at Waterloo, Iowa, this 1st day of May, 1919.

FREDERICK J. HACKER.
